US00D979357S

(12) **United States Design Patent** (10) **Patent No.:** **US D979,357 S**
Wang (45) **Date of Patent:** **** Feb. 28, 2023**

(54) **PLANT WATERING SPIKE**

(71) Applicant: **ZHENPING COUNTY TINGYU TRADE CO., LTD.**, Nanyang (CN)

(72) Inventor: **Ting Wang**, Nanyang (CN)

(73) Assignee: **ZHENPING COUNTY TINGYU TRADE CO., LTD.**, Nanyang (CN)

(**) Term: **15 Years**

(21) Appl. No.: **29/858,024**

(22) Filed: **Oct. 27, 2022**

(51) LOC (14) Cl. **08-01**

(52) U.S. Cl.

USPC **D8/1**

(58) **Field of Classification Search**

USPC D8/1, 2; D23/213

CPC A01G 29/00

See application file for complete search history.
